United States Patent Office

Des. 223,279
Patented Apr. 4, 1972

223,279

BATH MAT OR SIMILAR ARTICLE

William D. Taylor, Wooster, Ohio, assignor to Rubbermaid Incorporated, Wooster, Ohio

Filed Nov. 5, 1970, Ser. No. 25,845

Term of patent 14 years

Int. Cl. D7—99; D5—99

U.S. Cl. D44—31

FIG. 1

FIG. 2

FIG. 3

FIG. 1 is a top plan view of a bath mat embodying my new design.

FIG. 2 is an enlarged plan view of a corner portion thereof.

FIG. 3 is an enlarged fragmentary sectional view on line 3-3 of FIG. 2.

The bottom of the mat, as indicated in FIG. 3, is substantially flat and plain.

I claim:

The ornamental design for a bath mat or similar article, as shown and described.
